SEWING MACHINE

Ernest Like, Portsmouth, Ohio, assignor to The Selby Shoe Company, Portsmouth, Ohio, a corporation of Ohio

Application March 11, 1941, Serial No. 382,764

2 Claims. (Cl. 112—62)

This invention relates to an improvement in a conventional type of Singer sewing machine. The structure of the invention is particularly useful in sewing certain shoe parts and an embodiment of the invention particularly adapted to this field will be herein disclosed as the preferred embodiment of the invention. However, the machine is not limited to this utility as will be apparent from the ensuing detailed description of its construction and operation.

The conventional Singer sewing machine used in shoe manufacture includes a flat standard or article support with which a shuttle and bobbin are associated and into which the needle enters on its downward stroke. In a conventional shoe sewing operation, such as, for example, the sewing of an upper to a flat outsole, this base is used as a support for one of the articles being sewn, in this particular instance, the outsole. In many of the conventional shoe sewing operations this standard or article support is not only not an impediment but is, in fact, an advantageous feature of the machine.

However, there are certain particular sewing operations, such as, for example, the sewing of an upper to an upstanding flange on a molded outsole in which this standard or article support is a great disadvantage because this type of sewing operation requires the formation of a stitch line at a point which it is impossible for the needle to reach because of the size and shape of this article support. Otherwise stated, the conventional sewing machine is not sufficiently flexible to meet a sewing problem which involves the attachment of a piece of material such as a shoe upper to an upstanding flange on a molded outsole where the attachment must be made along a line comparatively close to the outsole, for example, a fraction of an inch away.

In order to arrive at the solution of this particular problem, it has been the inventor's concept to simply eliminate the base or article support conventional in the type of sewing machine under consideration, and utilize as the sole article supporting surface the face of the shuttle and a tubular housing which journals and protects the shuttle and bobbin. This combination is sufficiently small in area to permit its positioning close to the base of the upstanding flange of a molded shoe article in the example under consideration and it can even be inserted in the toe of a shoe to provide a stitch line around the toe at a point near the sole.

Once having the concept of a complete elimination of the article support it has been a prob-

lem of the inventor to provide a housing for the shuttle and bobbin and the various other elements directly associated with them, to provide means for transmitting an oscillating movement to the shuttle and to provide and arrange the various elements necessary to the transmission of power through an angular arm extending from the power source to the shuttle.

One of the objects of the invention has been to provide a sewing machine having an article supporting head embodying a shuttle and bobbin, which is very small in area, in fact, little larger than the size of the face of the shuttle.

Another object has been to provide means for transmitting an oscillating motion to the shuttle through an angular arm extending from the sewing machine base to the shuttle face.

Another object has been the provision of a gear arrangement in the base of the machine through which power can be transmitted to a sectional shaft housed in the angular arm.

Another object has been the adaptation of the moving parts of the conventional sewing machine to the particular and unique object and problem under consideration.

Other objects and advantages will be apparent from the further and more detailed description of the invention when considered in conjunction with the drawing in which:

30. Figure 1 is a fragmentary front view of a sewing machine embodying the present invention shown partly in section and with a shoe placed in normal sewing position to better illustrate the utility of the invention.

35. Figure 2 is a fragmentary longitudinal sectional view taken through the base of the sewing machine.

Figure 3 is a detail view of one of the universal joints in the shaft which oscillates the shuttle.

40. Figure 4 is a fragmentary sectional view along the line 4—4 of Figure 2 and shows the adjustable connection between the shuttle shaft and the driving mechanism of a sewing machine.

45. Figures 5, 6, 7 and 8 are fragmentary top plan views of the up-turned end of the shuttle carrying arm illustrating in sequence the various positions of the shuttle in relation to the thread in each stitch cycle.

50. Figure 9 is a fragmentary sectional view along the line 9—9 of Figure 8.

Figure 10 is a perspective view of the up-turned end of the arm with the shuttle in position to be dropped in place.

55. Figure 11 is a view of the rear of the shuttle

illustrating the course of the bobbin thread from one extremity of the shuttle to the other.

Referring again to the drawing, a sewing machine base is indicated generally at 12, Figure 1. This base may be bolted to a table, bench or other suitable supporting element. A bracket 13 is affixed to the base by bolts 14 and carries an angular tubular arm indicated generally at 15. This arm may extend at right angles from the base. The upper casing 16 shown in dot-dash lines is affixed to the top of the base 12 or may be integral therewith. This upper casing houses conventional driving mechanism for the needle 21 and a cam (not shown) which drives the swinging arm 17, Figure 2. The machine may be powered by a motor and driven by pulleys and a belt in the usual manner. These elements constitute no part of the invention. They are not shown or described in detail.

The various elements associated with the operation of the needle 21 form no part of the invention but have been illustrated and may be briefly described to provide a complete understanding of the operation of the machine. A conventional adjustable presser foot 18 is mounted on a pivotal plate 19. Thin and flexible materials often gather or wrinkle directly in front of the needle when a presser foot is not utilized. However, when a presser foot is lowered to exert a relatively light pressure on the material, it will smooth out the wrinkles before they reach the needle. In the case of the shoe, as illustrated, the material will not gather or wrinkle, but the foot when lowered to exert a light pressure on the leather will hold the shoe firmly in place and prevent it from being jerked upwardly during the up-stroke of the needle. The ears 20-20 attached to the plate 19 are also conventional and enable the operator to rotate the plate carrying the presser foot and thereby keep the foot 18 aligned longitudinally with the stitch line. In the drawing, the foot 18 is raised slightly from the shoe and turned at right angles to the stitch line for illustrative purposes. The needle 21 which may be removable is affixed in a reciprocating chuck 22 and is threaded in the usual manner. In its downward stroke the needle passes through a slot (not shown) in the presser foot 18.

As illustrated in Figure 4, the swinging arm 17 carries a roller 23 loosely mounted on one end and engaged in a slot 24 of a block 25 adjustably carried on a rack bar 26. The block 25 is affixed to the rack bar 26 by means of a set screw 27. The rack bar 26 includes a gear rack portion 28 at one end which is adapted to engage a gear 29 pinned on a vertical shaft 30. This gear 29 is enclosed in a housing 31 which is fixed to the inside of the base by the bolts 14 engaging flanges 32 on either side of the housing as best shown in Figure 2. The gear rack portion 28 of the bar 26 passes through an opening 33 in a wall 34 of the housing to engage the gear 28. At its other end, the rack bar 26 is slidably journaled in a wall of the base 12.

The vertical shaft 30 extends through an opening in the bottom wall 35 of the housing and is held in place by a collar 36 pinned to the shaft above the bottom wall and a bevel gear 37 pinned to the shaft directly below the bottom wall 35. A second bevel gear 38 pinned to a shaft 39 meshes with the bevel gear 37. The shaft 39 extends at right angles to shaft 30 through a bore 40 in the section 41 of the bracket 13 and continues out through a bore 42 in the angular tubular arm 15. The first section 43 of the arm 15 may ex-

tend at right angles to the base 12. The second section 44 may be turned upward at an angle of approximately 45° and the third section 45 may be turned upward perpendicular to the first section 43, all as illustrated in Figure 1. The various sections of the shaft may be joined by the universal joints 46-46. These joints may be exposed by notches in the arm to prevent binding.

At the uppermost end of the third section 45 of the shaft 39 an enlarged head 47 is provided and this head is journalled in a counterbore 48 of the vertical arm portion 45. A key 50 is fixed to this head 47 as at 51, Figure 9, and is adapted to ride in a second and larger counterbore 52 in the vertical arm section 45.

The shaft 39 may also include an extension 53 to the right of the bevel gear 38. This extension carries an arm 54 pinned to the end thereof and adapted to engage a bolt 55 projecting inwardly through the wall 56 of the base. This arm engages the bolt at the terminus of each stroke and constitutes a positive stop. This shaft extension 53 may be journalled in a bushing in the cross bracket 57 in the base. The cross bracket 57 cooperates with a collar 58 to hold the shaft against axial displacement.

As best shown in Figures 9 and 10 a shuttle 59 is provided with a spline 60 adapted to be loosely engaged by the key 50 when the shuttle is positioned in the counterbore 52. The distance from the top of the head 47 to the upper edge of the vertical arm section 45 should slightly exceed the height of the shuttle in order to allow the passage of the thread beneath the shuttle without disturbing the positioning of the shuttle in the counterbore. The shuttle 59 includes a bore 61 which houses a bobbin 62. A lip 63 configurated to catch the needle thread 64 on the return stroke as illustrated in Figures 6 and 7 is provided in the outer periphery of the shuttle. The walls 65 and 66 of the spline 60 taper toward the top and bottom of the shuttle as shown at 67 and 68. Clearances at 69 and 70 are provided between the key 50 and the shuttle spline 60 as shown in Figure 8.

The bobbin thread is dropped through the opening 71 in the bottom of the shuttle pulled upward through a slot 72 (see Figure 11) then threaded through the bore 73 to the top of the shuttle.

A portion of the arm 45 is cut away as at 74 and a groove 75 is provided in the arm below the counterbore 52 in alignment with the cut-away portion to provide a way for the needle 21. A housing 76 may be provided over this needle way.

In the operation of the machine the swinging arm 17 imparts a reciprocating motion to the bar 26. The gear rack portion 28 of the bar meshes with the small gear 29 and bevel gear 37 meshes with bevel gear 38 on shaft 39. This imparts an oscillating motion to the shuttle driving shaft 39 and in turn imparts a similar motion to the shuttle.

The above description includes so much of the entire structure as represents the improvement provided by the invention. The exact operation of the machine which will be hereinafter described is no different from the conventional operation of a sewing machine of the Singer type for sewing a lock stitch. However, in order to make a complete disclosure of the entire machine and its operation, this further description is included.

Sewing operation

In Figure 5 there is illustrated the position of the shuttle at rest with a length of the bobbin thread 80 projecting through the bore 73. As the operation begins, the shuttle 59 is moved clockwise to the position shown in Figure 6 with the lip 63 directly to the left of the slot 74. The needle 21 then moves to its downward position and as it does so places a portion of the needle thread 64 in the return path of the lip. However, as the shuttle was moved to the Figure 6 position before the needle came down the bobbin thread 80 is then at the left of the needle.

Figure 7 illustrates the first phase of the return stroke. The lip 63 has picked up the thread 64 and is carrying it along. Since the shuttle 59 fits loosely in the counterbore 52 and since the head 47 has a somewhat smaller diameter than the shuttle and has its top edge rounded as at 81, it will be seen that the thread 64 will readily pass beneath the shuttle as shown in Figure 9.

Since, as previously stated, the distance from the top of the head 47 to the upper edge of the arm 45 is slightly greater than the height of the shuttle, the thread 64 is free to pass below the shuttle. However, on the return stroke the length of bobbin thread 80 will be blocked by the needle 21 and the thread 64 which passes through the opening in the lower portion of the needle in the conventional manner.

In Figure 8, the shuttle has returned to its position at rest. Immediately upon reaching this position the needle is retracted, thus thread 64 is drawn up and tightened about the extended portion of the bobbin thread 80. As previously described, the wall 65 of the shuttle spline is tapered toward the top and bottom of the shuttle as at 67-67. This allows the thread 64 to be slipped from the lip 63 through the clearances provided at 69 and 70. The thread 64 will then come in contact with the tapered spline wall 66 and move the shuttle counter-clockwise until the key 50 abuts the spline wall 65 thus providing a clearance as shown at 82, Figure 5, to allow the thread 64 to pass free of the shuttle and to be tightened about the bobbin thread.

When a shoe such as 85 is in place as shown in Figure 1 and the machine completes the cycle as described, one lock stitch is formed. The molded sole 86, which is a type of shoe outsole formed from a single piece of sole leather having its outer edges turned upward to provide an

upstanding flange, may be sewed to the upper by the illustrated use of the machine of the invention. It will be noted that the stitch line in the example is quite close to the bottom or base portion of the molded sole and extends completely around the sole. A stitch line so positioned would have been absolutely impossible in a sewing machine of the conventional type because of the interference of the article support. This difficulty would have been encountered particularly in providing the stitch line around the toe which is essential to the sewing operation desired.

Through the use of the machine of the invention it has been found possible to provide various designs of shoes embodying the molded sole which previously had been sewed entirely by hand. An entirely new line of designs has been opened up by reason of the invention. However, as previously stated, it is apparent that the invention will have utility in other shoe sewing operations and in fields other than that of shoe manufacture. The particular sewing operation herein described is given only as an example but does indicate the potentialities of the machine.

Having fully described the invention, I desire to be limited only by the ensuing claims:

1. In a sewing machine, a base, a tubular arm extending laterally of said base for supporting a shuttle and providing a work support, said arm consisting of a main horizontal portion, said horizontal portion having a vertical extension at its outer end integrally formed therewith, a shuttle loosely supported in said vertical extension, and means for imparting an oscillating motion to the shuttle through the arm, said means consisting of a flexible shaft, said shaft disposed in and generally following the axis of the arm and having the upper end of its vertical portion provided with means for driving the shuttle.

2. In a sewing machine, a base, a tubular arm extending laterally of the base for supporting a shuttle and providing a work support, said arm including a main horizontal portion, a vertical extension at the outer end thereof and an oblique portion connecting the horizontal portion and vertical extension, a shuttle loosely supported in said vertical extension and means disposed within the arm and extending from the base to the shuttle for imparting an oscillating movement to the shuttle.

ERNEST LIKE.
